UNITED STATES PATENT OFFICE

JOHN ROCKE, OF BLOOMINGTON, ILLINOIS

WASHING MACHINE

Application filed May 26, 1926, Serial No. 111,693. Renewed June 30, 1927.

This invention relates to washing machines.

One of the objects of the invention is in the provision of a washing machine of the 5 agitating disk type, the same including driving mechanism therefor of simple design, and doing away with the multiplicity of parts which usually accompanies this type of drive.

10 Another object thereof lies in the provision of a washing machine of the agitating disk type, wherein the disk member is formed of phenolic condensation product, with the result that the agitation of the disk is accomplished with the minimum amount of power.

Still another object lies in the particular fashioning of the mechanism for clutching and unclutching the rack bar from the driving gear.

15 A further object lies in the provision of a washing machine having a hinged lid portion, said lid portion having formed upon its under side a series of corrugations providing a wash board surface.

20 Other objects will appear in the following specification, taken in connection with the annexed drawings, in which—

Fig. 1 is a side elevation of the washing machine, with portions thereof cut away for 25 a more detail view;

Fig. 2 is a plan view of the washer from above; and

Fig. 3 is a side elevation, partially in cross section, for a more detail showing of the 30 cover and clutching mechanism.

Referring to the drawings, we find the tub portion 7 assuming the shape of the so-called French square.

The body of the tub consists, in general, 35 of a substantially flat bottom portion 8, and a vertical side wall 9. The bottom and side wall are connected by a symmetrical curved portion 10 in such a manner as to gradually merge the bottom with the side wall without 40 the formation on the inside of the tub of any abrupt breaks or obstructions. Downwardly projecting portions 11 on the tub provide means for attachment, shown at 12, for the leg portions 13. It might be noted 45 that three of the legs are attached in the

above described manner, but that the fourth leg is connected to a housing for the driving mechanism, the same to be described in detail later.

Slidably related to the leg portions 13 are 55 the members 14 carrying the casters 15. Means for adjustably relating the members 14 with respect to the leg portions 13 is provided in the set screws 16. Brace rods between the lower ends of the leg portions are 60 shown at 17, and attached to said braces is the base 18, to which is connected, as at 19 and 20, the electric motor 21, which transmits power to the operating portions of the washer now to be described.

65 A housing 22 for the driving mechanism of the washer substantially surrounds all of the moving parts, and is attached as at 23 to one of the depending portions 11 of the tub, said housing also being connected with 70 one of the leg portions 13. Attached to the housing 22, as at 24, is a cylindrical casing 25 which provides at its upper end a seat for the wringer mechanism, which may be

75 of any desired type, said casing also carrying therein the wringer drive shaft 26, which has the well known clutch portion 27 mounted upon its upper end. The housing 22 is supported interiorly by brace 28 attached as at 29 thereto, said brace fixedly engaging a 80 bracket 30, which is bolted, as at 31 and 32, to a downwardly projecting portion 33 that provides the support for the disk driving mechanism. This support 33 is integrally cast with a base member 34, which is fastened 85

to the bottom of the tub 10 in a watertight manner. Projecting upwardly, as at 35, from the member or base 34, is a cylindrical hous- 90

ing. Returning to the driving means for the washer, we find a belt 36 connecting the electric motor with a belt wheel 37. A worm gear 38 having its bearings in the housing 22 is driven by said belt wheel and transmits power to an adjacent gear 39, the same being 95 connected to a stub drive shaft 40, which has bearings in the housing 22. The upper end of the stub drive shaft 40 has a crank 41 attached thereto, the outer end of said crank having

100 pivotally connected thereto, as at 42, a rack

bar 43, said rack bar engaging a driving gear 44 disposed on the lower end of the disk drive shaft 45 and adapted, due to its reciproca-
tion, to transmit a similar movement to said
drive shaft. Bearings 46 and 47 maintain
the drive shaft in a proper relation to the
upwardly projecting cylindrical casing 35.
Fixedly attached to the upper end of the disk
drive shaft 45 is a square lug 48, the same
being adapted to engage a similarly shaped
aperture in the upper portion of an agitator
member generally referred to as 49. The agi-
tator 49 consists of a substantially flat disk
49a arranged adjacent to the bottom of the
tub, and a central tubular member 49b arising
from the upper surface of the disk. The disk
and tubular member are connected by a
curved surface 49c, the curvature of this sur-
face being substantially that of the surface
previously described as connecting the
bottom of the tub with the side wall thereof.
This agitator 49 has a plurality of blades 50
thereon, the entire agitation being made of
a phenolic condensation product which is very
light in weight and well adapted for use in
washing operations. The agitator, as above
described, has a slideable, but positive, connec-
tion with the upper end of the drive shaft, a
washer 51 being disposed between the lug 48
and the upper edge of the housing 35. A
bearing surface 52 is provided interiorly of
the agitator to provide centering of the disk
with respect to the member 35.

A gear 53 on the stub drive shaft 40 meshes
with an adjacent gear 54, fixedly attached to
the lower end of the wringer drive shaft 26,
with the result that power is transmitted to
said drive shaft. Means for interrupting the
movement of the disk is provided in the fol-
lowing mechanism which is adapted to con-
trol the meshed or unmeshed relationship of
the rack bar 43 with the gear 44. A manually
operable handle 55 is securely attached to the
upper end of a rod 56, the latter being pivoted
at its upper end in an outwardly projecting
portion of the tub. The lower end of the rod
is similarly pivoted in a bracket 57. At-
tached to the projecting lower end of the rod
56 is a crank 58 having a downwardly pro-
jecting portion 59, to which is adjustably at-
tached the main clutch lever 60. The inner
end of this clutch lever 60 has a pivotal con-
nection 61 with a rack controlling member
62, which is pivoted, as at 63, with respect to
a portion projecting downwardly from the
bottom of the tub. The rack controlling
member 62 is not, in itself, adapted to im-
pinge the outer side of the rack, but there is
provided, as clearly disclosed in Fig. 3, a
roller portion 64 bolted thereon in the manner
shown at 65. The roller member 64 actually
engages the outer face 66 of the rack, as
shown in detail at 67. Upon disengagement
of the roller 64 from the rack 43 by movement
of the roller through the handle 55 and link

connection, the rack 43 will be moved out of
engagement with the driving gear 44 through
the blows imparted thereto by said gear. If
desired, however, the inner end of the rack 43
may be connected to a spring arranged to pull
said rack away from the driving gear when
the rack is released by turning the handle 55
in the proper direction.

It is obvious from the above that manual
manipulation of the control handle 55 will
move rack control member 62 and roller mem-
ber 64 thereon into and out of engagement
with the rack bar, with the consequent result
that the rack is either held in engagement
with the gear 44 or disengaged by the release
of said member.

The tub portion 10 has a surrounding rim
68 fixedly attached, as at 69, to the periphery
of the tub and extending a substantial dis-
tance inwardly from the outer edge thereof.
The actual lid for the tub is shown at 70, and
has the hinged portions 71 permitting raising
of the lid for the entrance and removal of
the clothes. This cover or lid 70 is made of
bakelite, as is the disk member.

Upon the under side of the lid and formed
integrally therewith are a series of corruga-
tions 72, providing a washboard to be used in
a manner later to be described.

Referring to the operation of the machine,
the transmission of power from the electric
motor may readily be followed through the
train of gears, to the reciprocation of the
rack bar, with a similar movement being
transmitted to the gear 44, and consequently
to the bakelite disk 50. The agitating move-
ment of the bakelite disk creates a violent
water disturbance, which finally results in
the cleansing of the clothes that are placed
therein. Similarly, the driving connection
to the wringer shaft may readily be seen.

With respect to the clutching and unclutch-
ing of the driving mechanism for the disk, it
is apparent that release of the rack control
bar 62, by manual movement of the handle
55, will result in the cessation of movement
of the gear 44, and consequently the bakelite
disk 49. Opposite movement of the control
handle will operate in a like manner to force
the rack into engagement with the gear 44,
with a continued movement or agitation of
the disk.

Upon reciprocation, the agitator appar-
ently hurls the water initially outwardly
from the base thereof along the horizontal
bottom and toward the sides, where it is
diverted upwardly by contact with the in-
clined portion between the sides of the tub
and the bottom. After traveling upwardly
along the sides a limited distance which va-
ries with the speed at which the agitator is
operating, the liquid flows inwardly toward
the center of the tub, whereupon it again con-
tacts with the agitator and is hurled around
the path just described. This operation is

repeated in a continuous cycle with the result that the liquid is caused to travel continuously in a substantially smooth and symmetrical path.

- 5 The general agitation of the liquid in the applicant's washing machine is modified by the formation of the tub in a substantially rectangular shape, it having been found that when an agitator of the type illustrated by 10 the applicant is used in combination with a tub of rectangular form the resulting agitation is greater than would normally be expected for the reason that the corners of the tub produce a baffling action on the liquid.
- 15 With respect to the use of the bakelite disk, it might be said that heretofore washers of this same general class have utilized, substantially in all instances, metal disks. Applicant, by using bakelite has greatly decreased the weight of the disk, while at the same time adhering to a size substantially that of the metal disks. By using bakelite, which is a composition of matter, a disk is provided which has all the better qualities 25 of the metal disks, such as strength and imperviousness to water, as well as the important advantage of being very light in weight. In washers of the present type, as stated before, the disks have been, in practically every 30 instance, formed of metal. In view of the fact that due to the underneath drive and the necessity of correct alignment of the vertical drive shaft, the disk must be balanced very carefully with respect to the upwardly 35 projecting casing or cylinder, in the present instance, 33. Metal disks, due to their imperviousness to liquid, and therefore non-warping qualities, could readily be used, but there remained the disadvantage of excessive weight. The reciprocation of a disk of 40 considerable weight is obviously attended by the necessity of a large amount of power as well as strain upon the driving mechanism. A heavy metal disk imposes, upon its initial 45 return movement after reciprocation in one direction, a considerable strain which is not present when applicant's bakelite disk is used. Bakelite has a much lower specific gravity than metal, and hence the attending lightness 50 in weight decreases to almost a negligible amount the strain upon the driving mechanism, and hence there results not only a longer lived washing machine, but also one operating with a smaller amount of power, and 55 in a much quieter and efficient manner.

Although wood dollies and disks have been used in a great many instances in the art, it would be impossible to use a wood disk in the present type of washer, inasmuch as it is impossible to prevent wood from warping, and any warping in the present type of washer would result in a binding about the vertically disposed cylinder, as well as an unbalancing of the disk, which would result in a strain, 60 and eventually wearing out, of the driving

mechanism. Again, it would be almost impossible to fashion a wood disk of the rather small size that normally these disks assume, that would survive under the vigorous reciprocation necessary to cause the proper water 70 action. If a disk were fashioned of wood that would be strong enough to stand the strain of this reciprocation, such disk would be not only unwieldy, but would require a great amount of power, in view of its size, to 75 create the necessary water action. The present bakelite disk answers all of the requirements of this type of washing machine, and its imperviousness to water, and its strength, adapt it peculiarly to the washing operation. 80

Also, this light weight disk is considerably easier upon the clothes, there being a distinct advantage over a heavy disk in this respect.

Use of the bakelite lid or cover has also permitted the fashioning of a washboard 85 upon the under surface with the result that garments or clothes that are extremely dirty may be rubbed by hand upon this surface, prior or during the washing action, to expedite the washing operation. 90

No drain for the tub has been shown in the present application, although it is apparent that any type of drain mechanism might be used, the same being located at the lowest point in the tub, and perhaps preferably in 95 the base portion 34.

What I claim is:

1. A washing machine having in combination a stationary tub having a vertical side wall and a horizontal bottom, the said side wall and bottom being connected with a symmetrical curved portion, and a reciprocating dolly within said tub, said dolly comprising a flat disk adjacent to the bottom of the tub, a tubular member arising from the center portion of the disk and terminating above the normal water line of the tub, the tubular member and disk being connected with a curved surface similar to the curved portion connecting the bottom and side wall, the curved portion of the dolly, the bottom of the hub between the dolly and the side of the tub, and the curved portion between the bottom and side being free from obstructions, so that upon reciprocating of the dolly, the liquid contents of the tub will be moved initially outwardly from the base of the dolly along the bottom of the tub, and upwardly over the curved surface between the bottom and the side wall in an uninterrupted manner. 100

2. A washing machine having in combination a substantially rectangular shaped stationary tub having vertical side walls and a substantially flat horizontal bottom, a downwardly and inwardly inclined portion connecting the lower edges of the side walls with the bottom of the tub, and a reciprocating bladed dolly within said tub lying adjacent the bottom thereof, the said flat bottom ex- 115 120 125 130

tending beyond the peripheral edge of the dolly.

3. In a washing machine, in combination,
a substantially square tub having side walls
5 and a bottom, a downwardly and inwardly
inclined curved portion connecting the side
walls with the bottom of the tub, and an oscil-
latable dolly within said tub and adjacent the
bottom thereof, said dolly consisting of a
10 plurality of blades and concave curved sur-
faces between the blades, the curved portion
connecting the side walls and the bottom and
the curved surfaces between the blades lying
approximately in the circumference of the
15 same circle.

In testimony whereof I have hereunto af-
fixed my signature.

JOHN ROCKE.
